UNITED STATES PATENT OFFICE.

SAMUEL L. ALLEN, OF CINNAMINSON, NEW JERSEY.

DESIGN FOR A CULTIVATOR-FRAME.

SPECIFICATION forming part of Design No. 19,367, dated October 22, 1889.

Application filed July 27, 1889. Serial No. 318,972. Term of patent 14 years.

To all whom it may concern:

Be it known that I, SAMUEL L. ALLEN, a citizen of the United States, residing at Cinnaminson, in the county of Burlington and State of New Jersey, have invented and produced a new and original Design for Cultivator-Frames, of which the following is a full and complete specification, reference being had to the accompanying drawing, forming 10 a part of the same.

The figure is a plan view of the cultivator-frame showing my design.

The leading feature of my design consists in an open oblong parallel-sided tool-holder 15 and an arm projecting at right angles thereto.

A is an oblong-shaped tool-holder having parallel sides and rounded ends and rendered

open or hollow by means of the interior parallel slots B B.

C is an arm projecting at right angles to 20 the tool-holder A at one side of the center, so as to form, not a symmetrical figure, but rather a figure somewhat L-shaped, as shown in the drawing.

I claim—

25 The design for a cultivator-frame herein shown and described.

In witness whereof I have hereunto set my hand.

SAMUEL L. ALLEN.
